Design No. 595

Dated August 30, 1853.

Des. 595

Garrettson Smith & Henry Brown
of Philadelphia, Pa.

Assignors to

J. G. Abbott & Archibald Lawrence of same place.
Letters Patent No. 595. Dated Augt 30th, 1853.

The schedule referred to in these Letters Patent, and making part of the same.

To all whom it may concern:

Be it known, that we, Garrettson Smith and Henry Brown,
of Philadelphia, in the County of Philadelphia, and State of Pennsylvania, have invented
or produced a new and original design in stoves, called the

"Hot Air Parlor,"

and we do hereby declare that the following is a full, clear, and exact description of the same; reference being had to the annexed drawings forming a part of this specification, in which

Figure 1 is a front elevation of the stove.

Figure 2 is an elevation of the foot.

In the several figures, but one half of each symmetrical design is given.

The fuel portion of this stove is contained within the Gothic arch a, and consists of the middle plate A supporting the grate, the upper cover B, and lower cover C. The middle plate A, is of a convex form, having the sunken panel c surrounded by the moulding d, and bearing upon its face the projections e, e', e'', the whole having the configuration and arrangement set forth in figure 1.

The upper cover B, has the form of a Gothic arch, and has near its edge the bead f. At the line g, the surface becomes more convex, and terminates at bottom in the flare g'. In the middle of the cover is the handle h, bearing the lozenge ornament i; and on each side of the handle is a sunken panel j, bearing the projections m, m', m'', in bas-relief. The panel is surrounded by the bead k; the whole design is arranged in detail as set forth in figure 1.

The lower cover C bears on each side of the handle h' a sunken panel j', ornamented in bas-relief with the projections l and l'. The lower portion projects, as seen at D, to cover the ash hole. The various details are fully represented in figure 1.

The Gothic arch a is surmounted by the ornament n, and on each side of the ornament is a sunken panel E, bearing in bas-relief the projections p, p', p'', the whole arranged as shown in figure 1.

The front of the stove bears the inscription, in raised capitals and numerals,

"Hot Air Parlor, Patented 1853; Abbott & Lawrence, Philadelphia,"

the several portions arranged as set forth in the drawing.

On each side of the curved portion of the front plate P, is a plinth R, which serves to support the tablet S, and also the Gothic arches q upon the tablet. In each plinth R is the sunken panel r bearing in bas-relief the projection s, s', s''. Upon the tablet S and within the arches q, are the flowers t, t', and projection u in bas-relief.

On the upper portion of the tablet S is the bracket G, of a scroll form, with the grooves a' in its front face, and the projections b' upon it. These brackets support the over-hanging top plate H, which is ornamented with the mouldings I, arranged as set forth in the drawing. The details of arrangement and configuration of the several ornaments and mouldings described above are fully set forth in figure 1.

The front of the base plate J, is ornamented with the moulding T, arranged as shewn in the drawing. The hearth is elevated above the base plate by the moulding O arranged horizontally to conform to the projection D of the lower cover C, as seen in figure 1.

The front W is surrounded in front by the rim x, and bears the star y in bas relief; the configuration and arrangement of details are fully shown in figure 2.

The stove is surmounted by the urn U, having the configuration shown in the drawing, and embellished by projections, drops, and pendants, as set forth in figure 1.

What we claim as our invention or production, and desire to secure by Letters Patent, is

The configuration and arrangement of the mouldings and ornaments on the front, top, and base of the stove, together with the form and configuration of ornaments on the front and urn, as fully set forth in this specification and annexed drawings, forming a new & original design for the stove, known as the "Hot Air Parlor."

In testimony whereof, we have hereunto signed our names before two subscribing witnesses.

Garrettson Smith.

Henry Brown.
